SAFETY CIRCULATION MEDIUM FOR WELL
CASINGSReuben C. Baker, Coalinga, Calif., assignor to
Baker Oil Tools, Inc., Huntington Park, Calif.,
a corporation of California

Application October 10, 1936, Serial No. 105,043

3 Claims. (Cl. 166—1)

This invention relates to the operation of casing deep oil wells.

There are instances during the lowering of the casing into an oil well bore, or during the cementing of the same in an oil well bore, that circulation downwardly through the casing is shut off. This may be caused by clogging of the casing or fittings on the casing along its length, or due to circumstances and conditions which prevent fluid from passing upwardly beyond a certain point along the casing between it and the wall of the bore. The many other reasons and circumstances which cause prevention of circulation downwardly through the casing are well known to those skilled in the art and are too numerous to set forth here.

It is the principal object of my present invention to fit the well casing with means uninterfering with circulation downwardly through the casing in the usual manner under normal conditions, but which means is responsive to increased pressure in the casing resulting from the shutting off of such normal circulation to provide a means of circulation above the point of shut-off.

In practicing my invention, I fit the casing intermediate its ends with a medium which is responsive to increased pressure within the casing to permit circulation through the side wall of the casing. The pressure to which such medium is responsive is preferably definitely greater than the pressure required for normal circulation downwardly through the casing and upwardly between it and the walls of the hole.

One form which the invention may assume is exemplified in the following description and illustrated by way of example in the accompanying drawing, in which:

Fig. 1 is a diagrammatic view showing a casing positioned in a well bore and constructed in accordance with my present invention.

Fig. 2 is an enlarged view in section of the casing showing my improved circulating plug fitted thereto.

Fig. 3 is an enlarged view in external elevation of the device shown in Fig. 2.

Fig. 4 is an enlarged fragmentary view in vertical section through the three ports disclosed in Fig. 1, showing the different diameters of the shear pins connecting the closure means to the casing.

Referring more particularly to the accompanying drawing, 10 indicates an oil well bore and 11 indicates the water string of blank casing therein. As previously pointed out the present invention is concerned with a safety medium for open-

ing a circulation port in the casing intermediate its ends when circulation cannot be established through the lower end of the casing. For this purpose the casing is formed with a radial aperture 11a through its side wall which is internally threaded to receive a bushing 12. The aperture 11a may be formed in a fitting interposed between casing lengths or may be formed directly in the casing itself, if it is so desired, and when I use the term "casing" herein, I mean either the casing lengths proper or any fittings connected therewith.

The bushing 12 is bored coaxially as at 15 so as to form a circulation port communicating at its inner end with the interior of the casing and at its outer end with the space exteriorly of the casing. Slidably fitting within the circulation port or bore 15 is a plug 16 which is hollow and cylindrical. The outer end of this plug 16 is closed as at 17 and the inner end thereof is open as illustrated. The inner end of the plug is surrounded by an exterior annular flange 18 of a diameter greater than the circulating port or bore 15. The length of the plug between the annular flange 18 and its closed outer end 17 is greater than the length of the port or bore 15.

The side wall of the plug 16 is formed with a radial port 19 closely adjacent to its outer end, as most clearly illustrated in Fig. 2. A transversely arranged shear pin 20 normally secures the plug 16 in the bore or circulating port 15 with its outer end flush with the exterior of the casing. In this position the radial port 19 in the plug 16 is covered by the wall of the bore 15 so that it will be ineffective to permit circulation through the plug and casing. The shearing strength of the pin 20 is so calculated that it will be sheared when the pressure on the plug from within the casing exceeds a predetermined value. I prefer that this pressure be definitely greater than the pressure normally necessary to establish and maintain circulation through the casing in the usual and normal manner. The margin of difference between the pressure necessary to maintain normal circulation and that necessary to shear the pin 20 depends, of course, on the operator's judgment and the depth of the well into which the casing is interposed.

When the pressure builds up in the casing to the predetermined point, the pin 20 will be sheared and the plug 16 will be moved radially outward with respect to the casing until the flange 18 engages the inner periphery of the casing, at which time the port 19 will be uncovered and disposed beyond the exterior of the casing so that

circulation can be established through the circulating port 15 from the interior of the casing to the space surrounding the exterior thereof.

It is obvious that should the auxiliary circulating port 15 and its associate mechanism just described be fitted to the casing at a point above its lower end and circulation should, for any reason, be shut off below such auxiliary circulating port, that a definite and predetermined rise of pressure 5 in the casing will be followed by shearing of the pin 20 and opening of the circulating port 15 so that circulation may be established at that point along the casing.

It is obvious, of course, that when circulation 15 is shut off at the lower end of the casing that the pressure in the casing will automatically rise until that pressure required to open the auxiliary circulating port 15 is reached.

In a long string of casing, as illustrated in Fig. 20 1, I may prefer to use more than one auxiliary circulating port 15 and I prefer that they be opened in response to progressively increasing pressures in the casing in an upward sequence. This is accomplished, of course, by merely progressively increasing the diameter of the shear 25 pins 20a and 20b of the upper closures of the circulating ports as shown in Fig. 4. In this arrangement circulation may be established at the lowest possible point above the point of shut-off 30 so that if circulation cannot be effected through the lower end of the casing, the pressure will rise to the point sufficient to open the first auxiliary circulating port, and if circulation cannot be broken at that point, pressure in the casing will 35 rise to open the next uppermost circulating port 15a and so on until circulation is established.

From the foregoing it is obvious that I have provided a very efficient medium for enabling circulation to be broken through the side wall of a

blank string of well casing above the point where circulation could not be established or maintained.

While I have shown the preferred form of my invention, it is to be understood that various 5 changes may be made in its construction by those skilled in the art without departing from the spirit of the invention as defined in the appended claims.

Having thus described my invention, what I 10 claim and desire to secure by Letters Patent is:

1. In combination with a string of blank well casing, said casing having a circulation port formed therein at an intermediate point therealong, a closure for said port, a shear pin normally maintaining said closure effective, said shear pin being capable of being sheared by a predetermined pressure in the casing to render said closure ineffective.

2. In combination with a string of blank well 20 casing, said casing having a plurality of circulation ports formed therein at longitudinally spaced intermediate points therealong, a closure for each port, shear means for each closure normally maintaining the same effective, said shear means 25 being sheared in an upward sequence in response to progressively increased pressures of predetermined value in the casing.

3. In combination with a string of blank well casing, a circulation port formed through the 30 side wall thereof, a plug fitting said port and closing the same, a shear pin connecting said plug to the casing and to maintain the same in a position closing said port, said shear pin being sheared by a pressure of a predetermined value 35 in the casing to render said plug ineffective in closing said port.

REUBEN C. BAKER.
